MULTISHUTTLE WEFT REPLENISHING LOOM

Victor H. Jennings, Worcester, Mass., assignor to
Crompton & Knowles Loom Works, Worcester,
Mass., a corporation of Massachusetts

Application January 28, 1942, Serial No. 428,458

18 Claims. (Cl. 139—232)

This invention relates to improvements in multi-shuttle weft replenishing looms and it is the general object of the invention to adapt such a loom for the replenishment of a comparatively small number of shuttles from a larger number of reserve stacks of bobbins.

In the weaving of certain fabrics it is desirable to effect mixing of the filling by the use of two shuttles which have alternate periods of activity. One shuttle may be active for a pair of picks and the second shuttle active for the next pair, in which case the complete shuttle sequence requires four picks of the loom. In such looms it is desirable to replenish each shuttle from a plurality of stacks of reserve bobbins for the purpose of effecting mixing of the weft and also to permit the use of multi-stack magazines with two shuttles.

According to the form of my invention illustrated hereinafter I employ a magazine having four stacks of reserve bobbins all provided with weft of the same general kind but wherein slight variations as to color or size may exist among the bobbins of the several stacks, and use two shuttles each of which is to be replenished from two stacks. It is an important object of my present invention to permit the accomplishment of this result by operating the magazine selector in such a manner that bobbins for transfer will be drawn from the several stacks in a more or less regular manner.

The usual multi-color weft replenishing magazine employs a plurality of vertical slides, one for each stack of bobbins, and a selector which can register with the several slides one at a time. When used for customary 4 x 1 weaving each stack will have its own distinctive type of reserve bobbin and there will be four shuttles having wefts corresponding to the stacks. A connection from the box motion or some part in time with it causes the selector to register with the stack corresponding to the active shuttle. In the present instance the bobbins are all of the same general kind and I construct and operate the selector so that it will replenish one shuttle from the front pair of stacks and the other shuttle from the rear pair of stacks. Another object of my invention is to operate the selector in a sequence of movements so related to the cycle of shuttle movements that a replenishing operation initiated by an exhausted shuttle when the selector is in register with one stack of a pair can be completed when the selector is in register with the other stack of the pair.

It is a further object of my present invention to provide a four-stack magazine to replenish two shuttles and construct the selector and vertical slides so that the loom can operate on an eight-pick cycle. As an example of such a cycle, the selector can be in register with the front

stack during the first pair of picks when one shuttle is active, in register with the third stack when the second shuttle is active, in register with the second stack when the first shuttle is again active, and in register with the fourth stack when the second shuttle is again active. I do not wish to be limited to this cycle, but in any variation of it the number of picks in the selector cycle will be a multiple of the number of picks in the shuttle cycle, or at least a multiple of two, so that the selector and shuttles may be kept in step with each other.

With these and other objects in view which will appear as the description proceeds, my invention resides in the combination and arrangement of parts hereinafter described and set forth.

In the accompanying drawings, wherein a convenient embodiment of my invention is set forth—

Fig. 1 is a side elevation of a weft replenishing mechanism made and operated according to my present invention.

Fig. 2 is an enlarged horizontal section on line 2—2 of Fig. 1, showing the selector in its extreme forward position and the relation it maintains to the lifting lugs of the vertical slides.

Fig. 3 is a detailed front elevation of the structure shown in Fig. 2, looking in the direction of arrow 3, and showing the relation of the lifting and depressing lugs of the slides relatively to the selector.

Fig. 4 is a horizontal section on line 4—4 of Fig. 3, showing the depressing lugs of the slides.

Fig. 5 is a diagrammatic view showing a pick sequence of shuttles.

Fig. 6 is a diagrammatic view showing the successive positions which the selector assumes with respect to the delivery slides for the several stacks.

Fig. 7 is a detail front elevation of a part of Fig. 1 looking in the direction of arrow 7, and

Figs. 8 and 9 show diagrammatically the control mechanism for the shuttle boxes and selector, respectively.

My invention relates to a well-known type of multi-color weft replenishing loom and I set forth herein only such parts of the mechanism as are involved in the changes which I make to adapt the loom for operation according to my invention. The loom frame 10, breast beam 11, lay 12, shuttle box 13, lay connector 14 and magazine M', except as mentioned hereinafter, are all of useful construction. The lay moves forwardly or to the right in Fig. 1 every beat of the loom and cooperates with two shuttles A and B both carrying the same kind of weft. As indicated in Fig. 5 the left end of the loom is provided with upper and lower shuttle boxes 20 and 21, respectively, which are alternately in active position with respect to the race plate 22 of the lay box. The boxes will be in the

55
50
55
60

down position for pick I to permit picking of shuttle A from box 20 to box 13. After arrival of shuttle A in box 13 the lay beats up and on the backward stroke shuttle A is picked to the left during pick II while the boxes are still down. The boxes then rise on pick III to permit shuttle B to be picked into box 13, after which this second shuttle is picked back to box 21 during pick IV while the left-hand boxes are up. The right-hand part of Fig. 5 is a repetition of the left hand part so far as the shuttle and shuttle box movements are concerned, the positions for picks V, VI, VII and VIII following as indicated in Fig. 5 to complete a sequence of eight picks. The shifting of the boxes 20 and 21 may be accomplished in any approved manner by mechanism to be referred to hereinafter.

From Fig. 5 it will be understood that shuttle A is in shuttle box 13 at the end of the first and fifth picks and the shuttle B is in box 13 at the end of the third and seventh picks, each shuttle returning to box 13 at four-pick intervals. Box 13 is empty on the even numbered picks, or when both shuttles are at the left and the boxes 20 and 21 shift.

The magazine M' comprises an inside plate 25 on which are mounted for vertical reciprocation four slides 24, 25, 26 and 27, respectively, corresponding to stacks 30, 31, 32 and 33, respectively, of reserve bobbins all of the same general kind. Each vertical slide cooperates with a gate or cradle designated generally at 35 which is normally empty when its slide is down. When the slide rises the cradle is rocked to receive a bobbin preparatory to a replenishing operation of the loom, and when the slide is depressed or returned to normal low position the cradle is rocked in the opposite direction to deliver its bobbin to a transfer position designated at T, Fig. 1.

A weft detector D is mounted in front of the box 13 and detects the condition of weft on the forward beat of the lay whenever a shuttle occupies box 13. By means of well-known mechanism indication of weft exhaustion by the detector D rocks the selector 40 in a counter-clockwise direction as viewed in Fig. 7 when the lay is on front center and an empty shuttle is in box 13. When the shuttle has been picked to the opposite side of the loom and the boxes 20 and 21 have shifted the color slide is given a clockwise angular movement as viewed in Fig. 7. These rockings of the color slide or selector may be effected by means of a vertical rod 42 actuated by an appropriate cam and connected at its upper end to a block 43 on which is pivoted an actuator lever 44 controlled by a pin 45 the position of which is determined by the detector D when rod 42 descends.

Each vertical cradle actuating slide is provided with a dog 46 which cooperates with a top shaft or setting mechanism 47 to set a transfer latch 48 in transfer position for engagement with a lay bunter 49 whenever shaft 47 is rocked in a clockwise direction as viewed in Fig. 7. The shaft 47 remains at rest as the vertical slides rise, being rocked only by down motion of any of the slides. Return motion of shaft 47 to normal position is effected by a resetter 50 mounted for engagement with the lay and pivoted as at 51 to a carrier 52 connected by link 53 to the shaft 47. Whenever the latter rocks in a direction to set the magazine for transfer as a result of down motion of a vertical slide the resetter 50 is moved rearwardly. Subsequent forward mo-

tion of the lay advances the resetter 50 and the latter acts through the mechanism connected to it to restore shaft 47 to normal position.

The selector 40 is mounted in usual manner for sliding motion in a horizontal direction under the action of a positioning lever 60 pivoted as at 61 and having engagement with a collar 62 secured to shaft 40. A rearwardly extending arm 64 on lever 60 is connected to a chain or link 65 which exerts a downward pull for the purpose of moving the selector 40 to the left as viewed in Fig. 1, while a spring 66 acts in usual manner to rock lever 60 in a clockwise direction for the purpose of moving the selector 40 to the right. The lever 60 and selector are capable of four different positions which are determined by a mechanism to be mentioned and operating in timed relation with the boxes 20 and 21.

20 The matter thus far described may be of common construction except as hereinafter noted, and reference may be had to Patent No. 1,030,748 for a further understanding of the structure and operation thereof.

25 In carrying my invention into effect I modify the selector and vertical slides as shown in Figs. 2, 3 and 4. The selector rod 40 is provided with a casting 80 having projecting front and back arms 81 and 82, respectively, provided with elongated fingers 83 and 84, respectively, which are parallel to the rod 40. The vertical slides 24, 25, 26 and 27 are provided respectively with upper lifting lugs 85, 86 and 87 and 88, respectively, and with lower depressing lugs 90, 91, 35 92 and 93, respectively. The lugs and fingers 83 and 84 are so proportioned that when the selector is in any one of its four controlling stations only one of the upper lugs can be engaged by the selector to raise its slide. When 40 the selector is in the extreme front position or the position next therebehind, as indicated at K and L in Fig. 6, the finger 83 lies over and can therefore actuate either of the bottom lugs 90 or 91. When the selector is in its third and 45 fourth positions finger 84 can actuate either of the bottom lugs 92 or 93 as indicated at M and N, Fig. 6. In Figs. 5 and 6 the reference characters K, L, M and N represent corresponding pairs of picks in the eight-pick sequence of movements of the selector in the order in which they occur.

50 In the operation of my invention, and assuming that the parts will follow the sequence suggested in Figs. 5 and 6, the shuttle boxes are down for picks I and II corresponding to pair K and finger 83 will be in register with lug 85 and all of the other upper lugs will be out of register with the fingers. Shuttle A is picked from the left to the right hand end of the loom and will be detected at the front center position of the lay between picks I and II. If exhausted, slide 24 will be raised by down motion of rod 42 and lifting of finger 83. In the type of loom to which my invention applies replenishment is not immediately followed by exhaustion of weft indication but occurs on a later pick when the empty shuttle returns to the replenishing end of the loom. The indicating shuttle, after returning to the left end of the loom will be moved to inactive position and shuttle B will become active for picks III and IV, or a pair L of Figs. 5 and 6. The selector has a corresponding rearward movement so that the finger 84 is in register with upper lug 87 and the downward motion of finger 84 which occurs as soon as the box shift is com-

pleted will be idle, since it is out of register with lugs 90 and 91. Assuming that sufficient weft is present in shuttle B no indication of weft exhaustion will be given and therefore slide 26 will remain in normal down position and shuttle B will return to the left end of the loom to be moved to lowered inactive position.

When the shuttle A returns to activity during picks V and VI for the pair indicated at M in Figs. 5 and 6, the selector will be moved forwardly one station so that finger 83, when moving downwardly immediately upon completion of the downward box shift, will depress the previously elevated lug 90 and a bobbin from the front cradle will be released for transfer and will be inserted into shuttle A between picks V and VI.

Replenished shuttle A then returns to the left end of the loom and shuttle B is again active, and this time the selector moves to its rearmost position, corresponding to picks VII and VIII representing the pair N in Figs. 5 and 6.

In the foregoing description of operation I have assumed a shuttle A will indicate weft exhaustion during the pair K and will be replenished during the pair M of picks, but it is to be understood that shuttle A could have given indication of weft during pair M of picks and be replenished at the beginning of the succeeding eight-pick sequence, and it is also to be understood that shuttle B could have given indication of weft exhaustion in pair of picks L and would have been replenished in pair of picks N. It will thus be seen that the selector controls the front pair of bobbin stacks 30 and 31 during the odd pairs of picks K or M when shuttle A is active and controls the rear pair of stacks 32 and 33 during the even number of pairs L and N when shuttle B is active.

I wish it to be understood that the particular sequence set forth herein is merely for illustrative purposes and it is within the spirit of my invention to assign any two stacks of bobbins to one shuttle and the other two stacks to the second shuttle and control the successive positions of the selector in a manner similar to that already described, causing the selector to register with either of two stacks when one shuttle is active and with either of two other stacks when the other shuttle is active.

Figs. 8 and 9 illustrate diagrammatically mechanisms for controlling the shuttle boxes and the magazine selector respectively. These figures illustrate the well-known Knowles head as a mechanism for effecting these controls, but I do not wish the shuttle box and selector control means to be limited necessarily to the disclosure of Figs. 8 and 9.

In Fig. 8 the chain 68 which determines the sequence of movements of the shuttle boxes comprises successive chain bars which provide right and left hand rows of indications. Since the shuttle boxes have only two positions the right hand row will be made up entirely of sinkers, but the left hand row is made of alternate pairs of sinkers 69 and intervening pairs of rolls 70. The chain moves over a cylinder 71 which has an angular movement every pick of the loom to present a new bar of the chain under the vibrator lever 72 on which is mounted a vibrator gear 73. The latter is actuated by upper and lower mutilated cylinders 74 and 75, respectively, and is attached by a connector 76 to a lever 77, the lower end of which has attached thereto a chain or other flexible connector 78 extending as indi-

cated in Fig. 8 to the box lifter rod 79 for the shuttle boxes already described. The chain 68 is assumed to move in the direction of arrow a to controlling position under lever 72 and the cylinders 74 and 75 cooperate with the vibrator gear 73 in the usual well-known manner to effect shifting of the shuttle boxes in response to the control exercised by the chain 68.

In Fig. 9 the mechanism for controlling the magazine selector is diagrammatically set forth and comprises a chain 100 having right and left hand rows 101 and 102 of sinkers 103 and rolls 104. The sinkers and rolls are arranged to give four different kinds of indications and move in the direction of arrow b around a cylinder 105 located under vibrator levers 106 and 107. These vibrator levers have mounted thereon vibrator gears 108 located between upper and lower mutilated cylinders 109 and 110, respectively. Right 20 and left levers 111 and 112, respectively, are attached by connectors 113 and 114 to the vibrator gears 108 and are given four different combinations of positions. A sheave 115 on the bottom of lever 112 has trained therearound the previously described chain 65. As indicated in Fig. 9 the chain 100 and the parts which it controls are not connected to shuttle boxes as usual but are used solely for the purpose of giving lever 60 and the selector 40 the four positions 30 already described.

It is to be understood that the pattern chains 68 and 100 move together and give simultaneous indication, pick after pick, to the parts which they control. Thus, the selector is kept in timed relation with the shuttle boxes and the previously described shifting of the selector with respect to the shuttle sequence is preserved.

From the foregoing it will be seen that I have provided simple means for adapting a multi-stack magazine for use with two shuttles wherein each shuttle can be replenished by bobbins drawn from more than one stack. It will also be seen that whenever a shuttle is in need of replenishment and gives indication of exhaustion one of the vertical slides of the magazine will be raised to initiate movement of a bobbin to transfer position, and at a subsequent pick when the exhausted shuttle returns to the magazine and of the loom, the previously raised slide will be depressed despite the fact that the color slide will be in different position. This is due to the overlapping relationship between the fingers 83 and 84 with respect to the bottom lugs 90, 91, 92 and 93. The bobbins will generally be wound with substantially the same length of weft, and although there is likely to be some slight variation, the general operation of my invention will cause the bobbins to be drawn in an approximately uniform order as regards the various stacks. There will therefore be little danger that one stack will become empty and effect loom stoppage through the filling fork while there still remains any considerable number of bobbins in the remaining stacks.

In the foregoing description it has been assumed that the weft of all the stacks and both shuttles is of the same general type, but I do not wish to thus be limited, since each shuttle has its own set of stacks and the shuttles can therefore carry diverse wefts. Furthermore, the shuttles need not necessarily follow each other at two pick intervals but may if desired remain for periods longer than two successive picks.

Having thus described my invention it will be seen that changes and modifications may be

made therein by those skilled in the art without departing from the spirit and scope of the invention and I do not wish to be limited to the details herein disclosed, but what I claim is:

1. In a weft replenishing loom operating with a pair of shuttles which are alternately active, a weft replenishing mechanism having a group of stacks of reserve bobbins for each shuttle, a releaser for each stack movable to initiate bobbin release from the associated stack and thereafter movable to complete bobbin release, a selector common to all the releasers, means to cause the selector to register with one of the releasers of the stacks of one group when the corresponding shuttle is first active and with the releaser of another stack of the same group when the same shuttle is again active and cause the selector to register with the releaser of one of the stacks of the other group when the other shuttle is first active and register with the releaser of another stack of said other group when the other shuttle is again active, means to cause the selector to have an operative initiatory bobbin releasing movement with respect to the releaser of any stack with which it registers to initiate bobbin release upon exhaustion of weft in either shuttle when active and thereafter cause said selector to have a bobbin releasing completing movement, and means on each releaser by which any releaser which is given an initiating movement due to exhaustion of the corresponding shuttle when active receives a bobbin releasing completing movement from said selector when the corresponding shuttle is next active.

2. In a weft mixing weft replenishing loom operating with a pair of shuttles which are alternately active, a weft replenishing mechanism having a group of stacks of reserve bobbins for each shuttle, a bobbin releaser for each stack movable to initiate bobbin release, a selector common to all the releasers and capable of movement into registry therewith, means to move the selector from registry with a releaser of one group to registry with a releaser of the other group when there is a change in the active shuttle and cause the selector upon occurrence of another change in the active shuttle to register with a releaser of the first group different from that with which it registered before leaving said first group, said means thereupon causing the selector to register with another releaser of said other group, and means to cause the selector to have an operative movement with respect to any releaser with which it is registered to initiate a bobbin release upon occurrence of weft exhaustion in the active shuttle.

3. In a weft mixing weft replenishing loom operating with two shuttles which are alternately active, two pairs of stacks of reserve bobbins, one pair for each shuttle, a releaser for each stack to have an initiating movement in one direction preparatory to bobbin release and a return movement in the opposite direction to complete bobbin release, a selector and actuator for the releasers having an actuating stroke in one direction whenever the active shuttle is depleted of weft to give the releaser aligned therewith an initiating movement and having an opposite stroke every second pick of the loom to effect return movement of a releaser previously given an initiating movement and aligned therewith, positioning means for the selector and actuator to align the latter with the pair corresponding to the active shuttle and cause said selector to be aligned alternately with the re-

leasers of any one pair for successive periods of activity of the corresponding shuttle, and co-operating means on said release mechanisms and said selector and actuator to cause the latter to be aligned with all the release mechanisms of the pair corresponding to the active shuttle when said selector has said opposite stroke.

4. In a weft replenishing loom operating with a pair of shuttles which follow each other in a four-pick cycle, in the first pair of picks of which one shuttle is active and in the second pair of picks of which the other shuttle is active, a weft replenishing mechanism having a group of stacks of reserve bobbins for each shuttle, a bobbin releaser for each stack, a selector common to all the stacks, means to give said selector a cycle of successive shifting movements, one shifting movement for each pair of picks, to cause said selector to be in registry with alternate groups on successive shifting movements thereof and cause said selector to be in alternate registry with the stacks of any one group on alternate shifting movements thereof, and means to cause the selector when in register with any stack to have a movement with respect to the corresponding releaser to initiate bobbin release when the shuttle corresponding to the group containing the releaser with which the selector is in register is exhausted of weft.

5. In a weft replenishing loom operating with two shuttles which are alternately active, a pair of stacks of reserve bobbins for each shuttle, a selector operating in a two-pick cycle and capable of having a bobbin release initiating motion in one direction in the first part of each cycle and having a bobbin release completing motion in the opposite direction in the latter part of every cycle, a bobbin releaser for each stack movable from normal position to bobbin release initiating position and then back to normal position to complete bobbin release, an element on each releaser located for actuation by a selector initiating motion when in register with said selector and the releaser is in normal position, a member on each releaser out of the path of said completing motion of the selector when in register with the latter and the releaser is in normal position but moved into said path when the releaser moves to abnormal position and the selector is in register therewith, positioning means to locate said selector in register with the members corresponding to the active shuttle and locate said selector in alternate register with the elements of either group during successive periods of activity of the same shuttle, and means to cause said selector to have an initiating motion when the active shuttle is depleted of weft.

6. In a weft replenishing loom operating with two shuttles which are alternately active, a pair of stacks of reserve bobbins for each shuttle, a selector operating in a two-pick cycle and capable of having a bobbin release initiating motion in one direction in the first part of each cycle and having a bobbin release completing motion in the opposite direction in the latter part of every cycle, a bobbin releaser for each stack movable from normal position to bobbin release initiating position and then back to normal position to complete bobbin release, an element on each releaser located for actuation by a selector initiating motion when in register with said selector and the releaser is in normal position, a member on each releaser out of the path of said completing motion of the selector when in register with the latter and the releaser is in normal position

but moved into said path when the releaser moves to abnormal position and the selector is in register therewith, positioning means to locate said selector in two zones of action, one zone for each pair of stacks, said positioning means causing said selector when in either zone to register with the members of the corresponding pair of stacks, and said positioning means registering said selector alternately with the elements of a given pair of stacks during successive locations of said selector in the corresponding zone, and means to cause said selector to have an initiating motion when the active shuttle is depleted of weft.

7. In a weft replenishing loom operating with two shuttles which are alternately active, a pair of stacks of reserve bobbins for each shuttle, a selector operating in a two-pick cycle and capable of having a bobbin release initiating motion in one direction in the first part of each cycle and having a bobbin release completing motion in the opposite direction in the latter part of every cycle, a bobbin releaser for each stack movable from normal position to bobbin release initiating position and then back to normal position to complete bobbin release, an element on each releaser located for actuation by a selector initiating motion when in register with said selector and the releaser is in normal position, a member on each releaser out of the path of said completing motion of the selector when in register with the latter and the releaser is in normal position but moved into said path when the releaser moves to abnormal position and the selector is in register therewith, the element and member of each releaser being out of alignment with each other with respect to the direction of motion of the releaser, positioning means to locate said selector in register with the members corresponding to the active shuttle and locate said selector in alternate register with the elements of either group during successive periods of activity of the same shuttle, and means to cause said selector to have an initiating motion when the active shuttle is depleted of weft.

8. In a weft replenishing loom operating with two shuttles which are alternately active, a pair of stacks of reserve bobbins for each shuttle, a selector operating in a two-pick cycle and capable of having a bobbin release initiating motion in one direction in the first part of each cycle and having a bobbin release completing motion in the opposite direction in the latter part of every cycle, a bobbin releaser for each stack movable from normal position to bobbin release initiating position and then back to normal position to complete bobbin release, an element on each releaser located for actuation by a selector initiating motion when in register with said selector and the releaser is in normal position, a member on each releaser out of the path of said completing motion of the selector when in register with the latter and the releaser is in normal position but moved into said path when the releaser moves to abnormal position and the selector is in register therewith, positioning means to locate said selector in two zones of action, one zone for each pair of stacks, said elements, members and selector being so related that said selector when in either zone registers with both members of the corresponding pair of stacks but with only one element of the pair of stacks, said positioning means registering the selector alternately with the elements of a given pair of stacks during successive locations of

75 said selector in the corresponding zone, and means to cause said selector to have an initiating motion when the active shuttle is depleted of weft.

9. In a weft replenishing loom operating with two shuttles which are alternately active, a pair of stacks of reserve bobbins for each shuttle, a selector operating in a two-pick cycle and capable of having a bobbin release initiating motion in one direction in the first part of each cycle and having a bobbin release completing motion in the opposite direction in the latter part of every cycle, a bobbin releaser for each stack movable from normal position to bobbin release initiating position and then back to normal position to complete bobbin release, an element on each releaser located for actuation by a selector initiating motion when in register with said selector and the releaser is in normal position, a member on each releaser out of the path of said completing motion of the selector when in register with the latter and the releaser is in normal position but moved into said path when the releaser moves to abnormal position and the selector is in register therewith, the elements of either pair of stacks being more widely spaced than the corresponding members and the selector having an actuator for each pair of stacks capable of registry with but one element at a time but registering with both members of a pair of stacks when registering with either element of the pair, positioning means to locate said selector in register with the members corresponding to the active shuttle and locate said selector in alternate register with the elements of either pair of stacks during successive periods of activity of the same shuttle, and means to cause said selector to have an initiating motion when the active shuttle is depleted of weft.

10. In a weft replenishing loom operating with a pair of shuttles operating in a four-pick cycle in the first pair of picks of which one shuttle is active and in the second pair of picks of which the other shuttle is active, a weft replenishing mechanism having two pairs of stacks of reserve bobbins, one pair of stacks for each shuttle, a bobbin releaser for each stack capable of having an initial motion preparatory to bobbin release, a selector common to all the stacks, positioning means for the selector operating in an eight-pick cycle and effective to shift the selector at two-pick intervals to cause said selector to register first with a given releaser of one pair of stacks for two picks when one shuttle is first active, then shift to registry for two picks with a given releaser of the other pair of stacks when the other shuttle is first active, then shift to registry for two picks with the other releaser of the first pair of stacks when the first shuttle is again active, and then register for two picks with the other releaser of the other pair of stacks when the other shuttle is next active, and means to cause the selector when in register with any releaser to have an operative movement with respect to the latter to initiate bobbin release when the corresponding shuttle is exhausted of weft.

11. In a weft replenishing loom operating with two shuttles which are alternately active for two successive picks each and requiring four picks for a complete shuttle sequence, a pair of reserve stacks of bobbins for each shuttle, a vertically movable bobbin releaser for each stack, a selector common to the releasers, a lifting lug on each releaser above the selector, a depressing

lug on each releaser below the selector and offset horizontally with respect to the corresponding lifting lug toward the other depressing lug of the same pair of releasers, a selector having a finger for each pair of releasers capable of registering with the corresponding lifting lugs one at a time only but registering with both depressing lugs of a pair of releasers when registering with either lifting lug thereof, positioning means for the selector to cause said fingers to be alternately registered with the depressing lugs of their respective pairs of releasers at two-pick intervals and cause either finger to register alternately with the lifting lugs of the same pair of releasers during successive periods of activity of the corresponding shuttle, and actuating means operative upon exhaustion of weft in either shuttle when active to cause the selector to raise a given lifting lug of the pair of releasers corresponding to the exhausted shuttle to initiate bobbin release, said actuating means thereafter causing said selector when registered with the other lifting lug of the last named pair when the exhausted shuttle is next active to depress the previously raised depressing lug to complete bobbin release.

12. A selector for a weft replenishing loom having two pairs of laterally spaced bobbin releasers each having a lifting element and a depressing member offset laterally from the lifting element, said selector having a body to extend laterally with respect to the releasers, and two fingers so located along said body that said fingers can register with but one lifting element at a time and each finger registers with both depressing members of the corresponding pair of releasers when registering with one or the other of the lifting elements of said pair, the other finger being out of register with the elements and members of the other pair of releasers.

13. A selector for a weft replenishing loom having two pairs of laterally spaced bobbin releasers each having a lifting element and a depressing member offset laterally from the lifting element, said selector having a pair of fingers to be disposed laterally of said releasers, there being one finger for each pair of releasers, each finger capable of registering with but one element at a time of the corresponding pair of releasers and when registering with either element being in register with both members of the pair, the other finger being out of register with the elements and members corresponding thereto.

14. Selector mechanism for a weft replenishing loom including a set of pairs of bobbin releasers and a selector, said releasers each having a lifting element and a depressing member and said selector having engaging means for the elements and members, said engaging means capable of registering with but one element at a time but registering with the pair of members corresponding to the element with which it registers, said means being capable of registering with but one pair of members at a time.

15. In a reserve bobbin magazine having two groups of stacks of reserve bobbins, a bobbin releaser for each stack, each releaser having a lifting lug and a depressing lug, a selector slideable on the magazine laterally of the releasers and common to the latter and capable of having a primary lifting motion and a subsequent depress-

ing motion, and actuating means on the selector for engagement with said lugs, said selector capable of assuming different laterally spaced positions, one position for each lifting lug, the lugs and actuating means being so related that the means can register with but one lifting lug at a time but registers with all the depressing lugs of the group containing the lifting lug registered therewith, said means capable of registering with the depressing lugs of but one group at a time.

16. In a weft replenishing loom operating with two shuttles which are alternately active, a pair of stacks of reserve bobbins for each shuttle, a reciprocable bobbin releaser for each stack capable of effecting bobbin release upon a complete reciprocation thereof, a selector capable of having a movement in one direction and having regularly recurring movements in the opposite direction, positioning means to effect shifting of the selector with respect to the releasers and effective to register said selector alternately with the releasers corresponding to either shuttle for successive periods of activity of the shuttle and effective to shift the selector from registry with a releaser of one pair of stacks to a releaser of the other pair of stacks whenever there is a change in the active shuttle, and means operative during activity of either shuttle to move the selector in said one direction to move the releaser aligned therewith in one direction during a period of activity of the corresponding shuttle when the latter is depleted of weft to initiate bobbin release and thereafter effective to move the selector in the opposite direction to complete a reciprocation of the previously moved releaser and complete bobbin release when the exhausted shuttle is next active.

17. In a weft replenishing loom operating with two shuttles which are active for alternate periods, a pair of stacks of reserve bobbins for each shuttle, a pair of bobbin releasers for each pair of stacks, one releaser for each stack, a selector and actuator mechanism for said releasers, and each releaser when operated effective to advance a bobbin in the corresponding stack toward transfer position, means to register said mechanism alternately with the pairs of releasers for successive periods of activity of the two shuttles and register said mechanism alternately with the releasers of either pair for successive periods of activity of the corresponding shuttle, and means operating jointly with said register means and effective upon depletion of weft in either shuttle to cause said mechanism to operate whichever releaser registers therewith of the pair of releasers corresponding to the depleted shuttle.

18. In a weft replenishing loom operating with two shuttles which are alternately active, a pair of stacks of reserve bobbins for each shuttle, a pair of bobbin releasers for each pair of stacks, one releaser for each stack, a selector for said releasers, means to cause the selector to register with one or the other of the releasers of the pair corresponding to whichever of the shuttles is active, and mechanism operative upon depletion of whichever shuttle is active to cause the selector to operate the releaser registered therewith in the pair of releasers corresponding to the depleted shuttle.
